TREATMENT OF HYDROCARBONS

Wayne E. Kuhn, Jackson Heights, N. Y., assignor,
by mesne assignments, to Texaco Development
Corporation, New York, N. Y., a corporation of
Delaware

Application July 20, 1937, Serial No. 154,531

3 Claims. (Cl. 196—49)

This invention relates to the treatment of hydrocarbon oils to produce therefrom lower-boiling hydrocarbon oils including motor-fuel constituents. More particularly, the invention relates to the treatment of a plurality of hydrocarbon oils of differing boiling ranges to produce therefrom motor-fuel constituents of high anti-knock value under conditions of highest efficiency.

10 It is an object of the present invention to provide a method of treating a plurality of hydrocarbon oils of differing boiling ranges, and intermediate products from said hydrocarbon oils, under optimum conditions for each different oil whereby maximum conversion to motor fuel of high anti-knock value is effected under conditions of highest over-all efficiency with minimum production of gas and deposition of coke and with a low requirement in apparatus.

20 It is a further object of the invention to provide a method of treating crude oil or partially topped crude oil to convert it to motor fuel of high anti-knock value under the conditions outlined above.

25 It is a further object of the invention to provide a novel and useful operating cycle for the treatment of crude oil having the above advantages and others which will be apparent from the following description.

30 The invention contemplates the separate treatment of a plurality of hydrocarbon oils of differing boiling ranges, which may be a light hydrocarbon oil, for example, heavy naphtha, a heavy hydrocarbon oil which may be reduced crude or 35 heavy gas oil and an intermediate hydrocarbon oil which may be a gas oil having a boiling range intermediate that of the said heavy hydrocarbon oil and said light hydrocarbon oil. The three hydrocarbon oils above mentioned may constitute the fractions produced from crude oil or 40 partially topped crude oil by distillation. The crude oil may be distilled by heating, for example, at a temperature of 500° to 800° F. at a pressure of 25 to 100 pounds per square inch and 45 fractionating resulting vapors whereby the crude oil is divided into a reduced crude, for example, one having an initial boiling point of 650° to 750° F., a virgin gas-oil condensate, for example, one having an end point of 650 to 750° F., a heavy 50 naphtha condensate, for example, one having an initial boiling point of 250° to 350° F. and an end point of 450° to 550° F., and a light naphtha distillate. Instead of fractionating the crude oil to produce reduced crude it may be further 55 distilled to produce a heavy gas-oil condensate

having the same initial boiling point as the reduced crude, which heavy gas oil may be used instead of reduced crude in the invention, as set forth in the following description and specific example.

5 According to the invention the heavy hydrocarbon oil, for example, reduced crude, is subjected to cracking conditions of temperature and pressure to effect a relatively mild cracking of the oil to lighter products which include a substantial proportion of constituents above the motor-fuel boiling range. For example, a reduced crude may be heated to a temperature of 850° to 950° F. at a pressure of 75 to 400 pounds per square inch for a time sufficient to effect 10 15 10% conversion to motor-fuel constituents. The cracked products from the mild cracking or viscosity-breaking treatment of the reduced crude are separated into vapors and liquid residue. The separation is effected under conditions suitable to 20 effect substantial vaporization of the cracked products whereby a heavy gas oil may be condensed from the vapors. This may be effected by the distillation of the hot products by application of heat thereto in the separating zone 25 or by admixture therewith of highly heated hydrocarbon vapors from another source, for example, from the reforming treatment of a heavy naphtha.

30 A light hydrocarbon oil which may be heavy naphtha produced by the distillation of a reduced crude is subjected to elevated conditions of temperature and pressure to effect reforming of the heavy naphtha to convert it to constituents of high anti-knock value. For example, 35 the heavy naphtha may be heated to a temperature of 950° to 1150° F. at a pressure of 500 to 1000 pounds per square inch for a time sufficient to effect the desired conversion. The hot products from such a treatment may be admixed 40 with the products of the mild cracking or viscosity-breaking treatment of the reduced crude described above for separation of the cracked products into vapors and liquid residue in a common zone whereby the highly heated vapors 45 from the reforming treatment assist in the vaporization of the cracked products of the viscosity-breaking treatment.

50 The vapors separated from the products of the viscosity-breaking and reforming treatments are fractionated to separate therefrom a heavy gas-oil condensate, for example, one having an initial boiling point of 650° to 750° F., a low-boiling gas-oil condensate, for example, one having an end point of 650° to 750° F., and a naphtha dis- 55

tillate. The naphtha distillate is preferably fractionated to separate therefrom a heavy naphtha condensate and a light naphtha distillate.

The heavy gas-oil condensate is separately subjected to cracking conditions of temperature and pressure to effect a mild cracking of the heavy gas-oil to lighter products including a substantial proportion of products above the motor-fuel boiling range. This cracking treatment preferably is somewhat more drastic than the treatment given the reduced crude because the clean, heavy condensate has less coke-forming tendency than the reduced crude. For example, the heavy gas-oil condensate may be heated to a temperature of 900° to 1000° F. at 75 to 1000 pounds per square inch for a time sufficient to effect approximately 15% conversion to gasoline constituents. The products of this cracking treatment are separated into vapors and liquid residue, and the vapors are fractionated to separate therefrom a heavy cycle stock, a lighter gas-oil suitable for more drastic cracking treatment, and naphtha distillate from which a heavy naphtha condensate may be separated. This separation and fractionation may be carried out in separate zones, but conveniently it may be accomplished by passing the cracked products from this operation to the separatory zone common to the viscosity-breaking and reforming treatment and effecting separation and fractionation of the cracked products of the treatment of the heavy gas-oil condensate in combination with the separation and fractionation of the products of the reforming and viscosity-breaking operations.

The lower-boiling gas-oil condensate separated from the products of the foregoing cracking operations is separately subjected to elevated conditions of temperature and pressure to effect conversion to lighter products including motor-fuel constituents. This operation may be carried out on a recycling basis whereby it is preferable to employ moderately drastic cracking conditions to effect maximum conversion to motor-fuel constituents of high anti-knock value consistent with minimum deposition of coke. For example, the lower-boiling gas-oil condensate and recycle stock may be heated to a temperature of 900° to 1050° F. at a pressure of 200 to 1000 pounds per square inch for a time sufficient to effect 20% conversion to gasoline constituents. The products of this cracking treatment are separated into vapors and liquid residue, and the vapors are fractionated to separate a recycle stock and a desired distillate in separatory and fractionation zones separate from those employed for the products of the previously described cracking operations. Separate separation and fractionation of these cracked products are advantageous since the naphtha distillate from this cracking treatment may be of relatively high anti-knock value and therefore would not require reforming. It is thus preferably collected separately.

A clean hydrocarbon oil intermediate in boiling range between the heavy naphtha and the reduced crude, which may be a virgin gas oil having an end point of 650° to 750° F. produced by the said distillation of crude hydrocarbon oil, is separately subjected to elevated conditions of temperature and pressure to effect drastic cracking thereof to lighter constituents including a substantial proportion of gasoline constituents of high anti-knock value. A hydrocarbon oil of this nature, especially a virgin gas oil, is particularly suited for drastic cracking treatment on a once-

through basis because of its low coke-forming tendency and relatively non-refractory nature. For example, the virgin gas oil may be heated to a temperature of 950° to 1100° F. at a pressure of 200 to 1000 pounds per square inch for a time sufficient to effect a 35 to 50% conversion to gasoline constituents. The products of the cracking treatment of the virgin gas oil are kept separate from the products of the cracking treatment of the reduced crude and heavy gas-oil condensate since the drastic cracking treatment of the virgin gas oil produces a naphtha of high anti-knock value which may not need reforming treatment. The products may be separated in a zone without admixture with other cracked products but conveniently may be treated in a common zone with the products of the cracking of the lower-boiling gas oil described above. In any case vapors separated from products of the cracking of the virgin gas oil are fractionated to separate a cycle gas oil which conveniently is admixed with the said lower-boiling gas oil for cracking treatment therewith.

The accompanying drawing is a diagrammatic view in elevation of apparatus suitable for carrying out the present invention. The invention will be further described in detail by reference to the drawing, but it is to be understood, however, that the invention is not limited by said drawing or by said specific description but is capable of other embodiments than those described and other embodiments which may be beyond the physical limitations of the apparatus illustrated.

Referring to the drawing, heaters 1, 2, 3, 4, 5 and 6 are indicated, each provided with a suitable pipe coil for the treatment of hydrocarbon oils of differing characteristics at different conditions of temperature and pressure. For purposes of simplicity the heaters 1 to 6, inclusive, are indicated as separate structures. It is to be understood, however, that a plurality of these heaters may be combined in a single furnace structure wherein a plurality of coils, each of which performs the function of one of the heaters, is mounted in the furnace in positions best suited for the heat treatment thereof necessary to effect the desired treatment of the hydrocarbon oil passing therethrough. For example, the functions of heaters 1, 2 and 3 may be formed by a like number of coils located in a single furnace structure and the functions of heaters 4, 5 and 6 may be performed by a like number of coils located in a single furnace structure.

In addition to heaters 1 to 6, inclusive, crude flash tower 7, combined evaporator and fractionator 8, bubble tower 9, evaporator 10, fractionator 11, condensers 12, 13 and 14 and gasoline receivers 15, 16 and 17 are indicated together with auxiliary equipment for carrying out the process of the invention.

Heater 1 is provided for the preliminary heating of crude oil or partially topped crude oil which is introduced to the system through line 18 by means of a pump 19 located in line 18. It is to be understood, however, that the preliminary heating of the crude oil may be accomplished by any suitable heat exchange with hot products in the system in place of or in addition to the use of heater 1, the use of which is shown merely for purposes of illustration. In heater 1 the crude oil is heated under pressure and temperature conditions suitable to effect the desired distillation in crude flash tower 7 into which the heated crude is introduced through line 20 which is provided with a valve 21 for any desired reduc-

tion in pressure. For example, the crude may be heated to a temperature of 500° to 800° F. at a pressure of atmospheric to 100 pounds per square inch.

5 Crude flash tower 7 is operated at a pressure of atmospheric to 100 pounds per square inch, and fractionation of the vapors from the distillation of the crude oil is effected by maintaining the upper portion of the tower at a temperature of 250° to 350° F. The distilled crude oil separates into vapors and liquid residue in the lower portion of the tower 7, and a bottom temperature of 650° to 750° F. is maintained to effect the desired distillation. Trap-out trays 22 and 23 are 10 provided in tower 7 above the point of introduction of the heated crude to collect a heavy naphtha condensate and a virgin gas-oil condensate, respectively. The heavy naphtha condensate collected in trap-out tray 22 may be one 15 having an initial boiling point of 250° to 350° F. and an end point of 450° to 500° F. The virgin gas-oil condensate collected in trap-out tray 23 may be one having an end point of 650° to 750° F. 20 The reduced crude collected in the bottom of tower 7 may be used for further treatment as such or may be further distilled to separate therefrom a heavy gas oil which may be employed for further treatment in place of the reduced crude. For purposes of illustration, however, the 25 invention is described as applied to the treatment of a reduced crude obtained in the above manner.

Reduced crude from the bottom of tower 7 is withdrawn through line 24 provided with a pump 35 25 and introduced into heater 2. In heater 2 the reduced crude is subjected to relatively mild cracking conditions to effect conversion to lower-boiling products including a substantial proportion of constituents lower boiling than the reduced crude but above the motor-fuel boiling range. For example, the reduced crude may be heated in heater 2 to a temperature of 850° to 40 45 950° F. at a pressure of 75 to 400 pounds per square inch for a time sufficient to effect the desired conversion. The cracked products from heater 2 are withdrawn therefrom through line 26 provided with a control valve 27 and introduced into the lower or evaporator portion of tower 8 for separation into vapors and liquid residue.

Heavy naphtha is withdrawn from trap-out tray 22 through line 28 provided with pump 29 and introduced into heater 6 wherein it is subjected to elevated conditions of temperature and pressure to effect reforming of the heavy naphtha and conversion thereof to constituents of improved anti-knock value. For example, the heavy naphtha may be heated in heater 6 to a temperature of 950° to 1150° F. at a pressure of 500 to 60 1000 pounds per square inch for a time sufficient to effect the desired reforming treatment. The hot reformed products are withdrawn from heater 6 through line 30 provided with a control valve 31 and introduced into the evaporator portion of tower 8 preferably by introduction into transfer line 26 whereby the volatile hot products of the reforming treatment assist in the vaporization of the vis-broken products from heater 2.

Tower 8 is maintained under conditions of temperature and pressure to effect the vaporization, in the lower portion thereof, of all but the heaviest portions of the cracked products introduced therein and the condensation, in the upper or fractionator portion thereof, of a heavy gas-oil condensate, for example, one having an initial

boiling point of 650° to 750° F. Fractionation is obtained by maintaining the top of the tower 8 at a temperature sufficiently low to permit passage overhead of products boiling at 650° to 750° F. and lower. For example, tower 8 may be 5 operated at a pressure of 10 to 200 pounds per square inch at a top temperature of 550° to 700° F. and a bottom temperature of 600° to 800° F. A trap-out tray 32 is provided in tower 8 at an intermediate portion thereof for the collection of 10 the heavy gas-oil condensate and to separate the tower 8 into a lower or evaporator section and an upper or fractionator section.

Heavy gas-oil condensate is withdrawn from trap-out tray 32 through line 33 provided with a 15 pump 34 and introduced into heater 3 wherein it is subjected to relatively mild or viscosity-breaking cracking conditions of temperature and pressure to effect conversion to lighter products including a substantial proportion of constituents 20 above the motor-fuel boiling range. In heater 3 the heavy gas oil is subjected to relatively more drastic cracking treatment than the crude oil in heater 2 because of the lesser coke-forming tendency of the clean heavy gas-oil condensate. 25 For example, in heater 2 the heavy gas-oil condensate may be heated to a temperature of 900° to 1000° F. at a pressure of 75 to 1000 pounds per square inch for a time sufficient to effect the desired conversion. The cracked products from 30 heater 3 are withdrawn through line 35 provided with control valve 36 and introduced into the evaporator section of tower 8 conveniently by admixture with the cracked products in transfer line 26 whereby the hot reformed products from 35 line 30 assist also in the vaporization of the products of the cracking treatment of the heavy gas-oil condensate.

A relatively heavy tar is withdrawn from the lower portion of tower 8 through line 37 provided with valve 38 for treatment elsewhere, for example, as fuel. When tower 8 is operated under substantial pressure the tar withdrawn through line 37 may be treated in a separate evaporator tower, not shown, to vaporize light constituents contained therein which may be recovered as condensate and returned to the upper part of tower 8 as reflux.

The vapors uncondensed in tower 8 pass overhead through line 39 provided with valve 40 and are introduced into bubble tower 9 wherein they are fractionated to separate a gas-oil condensate lower boiling than the heavy gas-oil condensate separated in tower 8, a heavy naphtha condensate and a light naphtha distillate which passes overhead. The desired fractionation is accomplished by maintaining the top of tower 9 at a temperature of approximately 300° to 400° F. at a pressure of 10 to 200 pounds per square inch. The bottom temperature may be maintained at 500° to 700° F. to effect the desired separation. A trap-out tray 41 is provided at a suitable point for the collection of a heavy naphtha condensate which may be withdrawn therefrom through line 42 provided with a valve 43 and introduced into line 28 for passage to the reforming heater 6.

The said lower-boiling gas-oil condensate is withdrawn from the bottom of tower 9 through line 44 provided with a valve 45 and a pump 46 and introduced into heater 4 wherein it is subjected to moderately drastic cracking conditions of temperature and pressure to effect conversion to lower-boiling products including motor-fuel constituents. For example, the low-boiling gas

- oil in heater 4 may be heated to a temperature of 900° to 1050° F. and a pressure of 200 to 1000 pounds per square inch for a time sufficient to effect the desired conversion. The hot products from the cracking treatment in heater 4 are withdrawn therefrom through line 47 and provided with valve 48 and introduced into evaporator 19 for separation into vapors and liquid residue.
10. Evaporator 19 is maintained under temperature and pressure conditions effective to cause vaporization of constituents suitable for further cracking treatment and lighter products, for example, all constituents boiling at 650° to 750° F. or lower. Evaporator 10 may be maintained at a pressure of 10 to 200 pounds per square inch to a bottom temperature of 600° to 800° F. The vapors separated are withdrawn from the upper portion of evaporator 10 through line 49 provided with a valve 50 and introduced into fractionator 11.
- In fractionator 11 the vapors introduced are fractionated to separate a reflux condensate and a desired distillate which consists of a gasoline fraction and lighter products. For example, to effect the desired fractionation fractionator 11 may be maintained at a pressure of 10 to 200 pounds per square inch with a top temperature of approximately 300° to 400° F. and a bottom temperature of 500° to 700° F. The reflux condensate collected in the bottom of fractionator 11 is withdrawn therefrom through line 51 provided with a valve 52. Line 51 preferably connects with line 44 whereby the reflux condensate is returned for further cracking treatment in heater 4, but it is to be understood that other and separate treatment of the reflux condensate may be effected.
- The liquid residue which collects in the bottom of evaporator 10 is withdrawn therefrom through line 53 provided with a valve 54 for use elsewhere, for example, as fuel. When evaporator 10 is operated under substantial pressure the liquid residue withdrawn through line 53 may be treated in a separate evaporator tower, not shown, to vaporize light constituents contained therein which may be recovered as condensate and returned to the upper part of tower 11 as reflux.
- Virgin gas oil is withdrawn from trap-out tray 23 through line 54 provided with a pump 55 and introduced into heater 5 wherein the virgin gas oil is subjected to drastic cracking conditions of temperature and pressure to effect a substantial conversion of the oil to lighter products including substantial proportions of high anti-knock motor-fuel constituents. For example, the virgin gas oil may be heated in heater 5 to a temperature of 950° to 1100° F. at a pressure of 200 to 1000 pounds per square inch for a time sufficient to effect the desired conversion. The cracked products from heater 5 are withdrawn therefrom through line 56 provided with control valve 57. Line 56 connects with transfer line 47 from heater 4 whereby the hot products of heater 4 and heater 5 are passed together to evaporator 10, and the cracked products from heater 5 are treated in evaporator 19 and fractionator 11 together with those from heater 4 in the manner described above.
70. Naphtha distillates uncondensed in towers 7, 9 and 11 are withdrawn therefrom through lines 58, 59 and 60, respectively, provided with valves 61, 62 and 63. Condensers 12, 13 and 14 are provided in lines 58, 59 and 60, respectively, for effecting liquefaction of the gasoline constituents

which are separated from accompanying gases in receivers 15, 16 and 17. Gases thus separated are withdrawn from the receivers through lines 64, 65 and 66 provided with control valves 67, 68 and 69, respectively. The gasolines thus separated may be withdrawn separately from the receivers through lines 70, 71 and 72 provided with valves 73, 74 and 75, respectively, or by means of line 76 which connects with receiver 15 and lines 78 and 79 which connect receivers 16 and 17, respectively, with line 76. Any desired blend of the gasolines produced in the system may be effected by suitable manipulation of valves 77, 80 and 81 located in lines 76, 78 and 79, respectively.

15. Cooling means such as reflux means or cooling coils 82, 83, 84 and 85 may be provided in the upper portion of towers 7, 8, 9 and 11, respectively, to effect desired fractionation therein. Auxiliary heating means such as heating coils 86, 87, 88, 89 and 90 may be provided in the lower portions of towers 7, 8 and 9, evaporator 10 and fractionator 11, respectively, to assist in maintaining the desired temperatures at those places.

The hot products passing through transfer lines 26, 30, 35, 47 and 56 may be suitably cooled, if desired, by heat exchange or by the admixture therewith of suitable cooling fluid prior to introduction into the respective separating zone, by means not shown.

25. Towers 7, 8, 9 and 11 are provided with suitable gas and liquid contact means to facilitate the absorption, condensation, stripping and evaporation which comprises fractionation. It is evident that the functions of the towers could be 30 performed by a fewer number, but the arrangement shown is for purposes of simplifying the illustration of the invention. For example, towers 8 and 9 could be combined in a single structure performing the functions of both.

35. In the apparatus illustrated no means is provided for disposing of materials collected in trap-out trays 22, 23, 32 and 41 and in the bottoms of towers 7, 9 and 11 other than for their further use in the system. It is to be understood, however, that the proportions of these intermediate products to be used may vary depending upon the quality of the raw material and the results desired. Separate means not shown may be provided for withdrawing portions of these intermediate products from the system, and it is to be understood that the invention is not limited to a process wherein all of each intermediate product is returned to the system.

40. According to a preferred modification of the invention a reduced crude, for example, one having an initial boiling point of 650° to 750° F. is heated in heater 2 to a temperature of approximately 880° F. at a pressure of approximately 200 pounds per square inch for a time sufficient to effect 10% conversion to gasoline products, and the cracked products are then passed through line 26 to the evaporator portion of tower 8. Heavy naphtha from trap-out trays 22 and 41 is heated in heater 6 to a temperature of approximately 1050° F. at a pressure of about 750 pounds per square inch for a time sufficient to effect reforming of the heavy naphtha to the desired degree. The cracked products from heaters 2 and 6 are separated in tower 8 into vapors 45 and liquid residue, and the vapors are fractionated to effect separation and collection in trap-out tray 32 of a heavy gas-oil condensate having an initial boiling point of 650° to 750° F. This heavy condensate is heated in heater 3 to 50

a temperature of approximately 950° F. at a pressure of about 400 pounds per square inch for a time sufficient to effect 15% conversion to gasoline constituents, and the cracked products are introduced into tower 8 for separation and fractionation therein.

The vapors passing overhead from tower 8 are fractionated in bubble tower 9 to separate therefrom a heavy naphtha which collects in trap-out tray 41, a gas-oil condensate having an end point of 650° to 750° F. which collects at the bottom of tower 9 and a naphtha distillate which passes overhead. The gas-oil condensate from the bottom of tower 9, together with cycle stock from the bottom of tower 11, is heated in heater 4 to a temperature of approximately 990° F. at a pressure of about 400 pounds per square inch to effect approximately 20% conversion to gasoline constituents.

20 Virgin gas oil from trap-out tray 23 is heated in heater 5 at a temperature of approximately 1010° F. at a pressure of about 750 pounds per square inch for a time sufficient to effect 35 to 50% conversion to gasoline constituents.

25 The cracked products from heaters 4 and 5 are separated in evaporator 10 into vapors and liquid residue. The vapors pass overhead into fractionator 11 wherein a reflux condensate is separated and naphtha distillate passes overhead.

30 The present invention thus provides a method of treating crude oil or reduced crude to convert it to gasoline of high anti-knock value wherein the various fractions separated from the crude oil and intermediate products prepared therefrom are each treated under optimum conditions to effect maximum conversion to gasoline of high anti-knock value under conditions of maximum efficiency and minimum formation of gas and deposition of coke. The operation of heaters 2 and 3 represents a two-stage treatment of the heavier constituents of the crude oil to effect maximum conversion to constituents suitable for further conversion with minimum production of gas and deposition of coke. The cracked products from these operations are relatively heavy whereby it is advantageous to admix therewith the hot products from the reforming treatment of the virgin naphtha to effect the desired degree of vaporization of the cracked products whereby a cycle stock for heater 4 may be obtained in trap-out tray 32. The vapors from this separation of cracked products are separately fractionated to obtain a lighter gas-oil cycle stock and a heavy naphtha for reforming treatment since the naphtha resulting from the mild cracking treatment of the reduced crude and heavy gas oil is ordinarily of low anti-knock value. On the other hand, the operation of heater 4 on a recycling basis and operation of heater 5 on a once-through basis effect maximum production in each case of high anti-knock naphtha consistent with minimum deposition of coke and formation of gas by the stocks treated. The vapors from these cracking operations are therefore separately fractionated since ordinarily no reforming of the naphtha is necessary. Heater 4 is operated under less drastic conditions than heater 5 since the feed therefor is ordinarily more refractory than the fresh feed for heater 5. The cycle stock recovered from the products of cracking in heater 5, however, is of a more refractory nature than the fresh feed from which it is obtained, and the cycle stock is therefore conveniently recovered with that from the cracked products from heater 4 for recycling to heater 4 for treatment therein.

These and many other advantages are apparent from the foregoing description which has been given for the purpose of illustrating the invention. It is to be understood, however, that the invention is not limited to the specific embodiments described or the apparatus illustrated but is capable of other embodiments which may be beyond the physical limitations of the apparatus indicated in the drawing.

I claim:

1. The method of treating hydrocarbon oils to produce therefrom lighter hydrocarbon oils including motor fuel constituents which comprises separating crude petroleum into vapors and residue in a primary separating zone and fractionating the separated vapors in a primary fractionating zone to form virgin gas oil and naphtha condensates, passing resultant residue to a single-pass viscosity-breaking zone wherein the residue is subjected to cracking conditions of temperature and pressure under viscosity-breaking conditions to effect conversion into lighter products including a substantial proportion of constituents above the motor fuel boiling range, delivering the resultant viscosity-broken products into a second separating zone, passing virgin naphtha condensate from the primary fractionating zone to a separate reforming zone wherein the naphtha is subjected to cracking temperature adequate to effect conversion of gasoline constituents into components of increased anti-knock quality, discharging the resultant reformed products at cracking temperature into said second separating zone to aid in effecting the separation of the viscosity-broken products into vapors and residue, passing the separated vapors from the second separating zone to a second fractionating zone wherein the vapors are subjected to fractionation to form heavy gas oil, lighter gas oil and naphtha condensates, directing heavy gas oil condensate from the second fractionating zone to a recycling cracking zone wherein it is subjected to cracking conditions of temperature and pressure to effect conversion into lower boiling products including a substantial proportion of constituents above the motor fuel boiling range, passing the resultant cracked products from said recycling cracking zone to said second separating zone wherein said cracked products are subjected to vaporization with the aid of the hot products from the reforming zone, passing virgin gas oil from the primary fractionating zone to a separate single-pass gas oil cracking zone wherein it is subjected to high cracking temperature under superatmospheric pressure and under conditions of high cracking per pass to effect conversion into motor fuel constituents of high anti-knock quality, directing lighter gas oil condensate from the second fractionating zone to a second recycling cracking zone wherein the oil is subjected to cracking conditions of temperature and pressure to effect conversion into motor fuel constituents, separating into vapors and residue the cracked products from the single-pass gas oil cracking zone and from the second recycling cracking zones externally of the separating and fractionating zones hereinbefore mentioned, fractionating the separated vapors in a third fractionating zone to form a desired distillate and reflux condensate and cycling reflux condensate from the third fractionating zone to the latter recycling cracking zone.

2. The method of treating hydrocarbon oils to produce therefrom lighter hydrocarbon oils including motor fuel constituents which comprises

separating crude petroleum into vapors and residue in a primary separating zone and fractionating the separated vapors in a primary fractionating zone to form virgin gas oil and naphtha condensates, passing resultant residue to a single-pass viscosity-breaking zone wherein the residue is subjected to cracking conditions of temperature and pressure under viscosity-breaking conditions to effect conversion into lighter products including a substantial proportion of constituents above the motor fuel boiling range, delivering the resultant viscosity-broken products into a second separating zone, passing virgin naphtha condensate from the primary fractionating zone to a separate reforming zone wherein the naphtha is subjected to cracking temperature adequate to effect conversion of gasoline constituents into components of increased anti-knock quality, discharging the resultant reformed products at cracking temperature into said second separating zone to aid in effecting the separation of the viscosity-broken products into vapors and residue, passing the separated vapors from the second separating zone to a second fractionating zone wherein the vapors are subjected to fractionation to form heavy gas oil, lighter gas oil and naphtha condensates, directing heavy gas oil condensate from the second fractionating zone to a recycling cracking zone wherein it is subjected to cracking conditions of temperature and pressure to effect conversion into lower boiling products including a substantial proportion of constituents above the motor fuel boiling range, passing the resultant cracked

products from said recycling cracking zone to said second separating zone wherein said cracked products are subjected to vaporization with the aid of the hot products from the reforming zone, passing virgin gas oil from the primary fractionating zone to a separate single-pass gas oil cracking zone wherein it is subjected to high cracking temperature under superatmospheric pressure and under conditions of high cracking per pass to effect conversion into motor fuel constituents of high anti-knock quality, directing lighter gas oil condensate from the second fractionating zone to a second recycling cracking zone wherein the oil is subjected to cracking conditions of temperature and pressure to effect conversion into motor fuel constituents, directing the resultant cracked products from the single-pass gas oil cracking zone and from the second recycling cracking zones to a third separating zone wherein separation of vapors from residue takes place, passing the separated vapors to a third fractionating zone wherein the vapors are fractionated to form a desired distillate and reflux condensate and cycling reflux condensate from the third fractionating zone to the latter recycling cracking zone.

3. The method in accordance with claim 1 wherein viscosity-breaker naphtha condensate from the second fractionating zone is combined with virgin naphtha condensate from the primary fractionating zone for passage to the said reforming zone.

WAYNE E. KUHN.
